UNITED STATES PATENT OFFICE

1,972,011

PROCESS FOR MANUFACTURING CARBON PAPERS

Armand Deplanche, Paris, France

Application May 26, 1932, Serial No. 613,736
In France May 28, 1931

1 Claim. (Cl. 91—70)

At the present time, the printed forms or carbon papers are obtained, either by printing with a typographic plate realized by means of a fatty ink keeping its copying power as long as it is not wholly dry, or by printing, at a hot state, of a wax ink solidifying by cooling and by passing the paper so printed upon a plate or a hollow cylinder cooled with a flowing of cold water.

10 In all cases, the copying material laid upon the paper, gives a superthickness which maculates the next sheets when these papers are stacked; it is necessary therefore to realize a storage at the well known manner.

15 Further, by drying and after a relatively short time, the copying power decreases fastly. Besides, in all process the actual manufacturing of the multiple documents prevents to coat the entire faces of the sheets and peripheral margins 20 are always necessary. In fact, if these margins are dispensed with, when the sheets are cut off and under the action of the cutting blade, the copying material is reported upon the corresponding non printed sheets.

25 This invention has for object to remedy to the aforesaid inconveniences and relates to a process for manufacturing carbon papers which consists to lay the copying material in a thin layer, at a manner known per se, upon the paper, but characterized in that this material is incorporated 30 by a pressure, at a hot state, into the paper, the excess of material being preferably removed so as to let substantially no superthickness on the paper.

35 The invention has also for its object to perfect the incorporation of the material by pressure into the paper, by a drying with heating of this material in order to obtain carbon sheets keeping indefinitely their copying power without maculating the adjacent sheets.

The invention has for further object means for carrying out the process and particularly the combination, in a same unit, with a container or inkstand for the copying material, of a delivering drum for lying this material upon the paper, of a scraper acting by pressure upon the paper passed between it and a support preferably constituted by a heating cylinder, so as this scraper acts both as a scraper for removing the material in excess and as a pressing member for entering the material into the paper, and also as a hot drier for the copying material.

The invention has for further object printed forms with multiple carbon sheets the binding 55 of which is performed by means of a pressed

wheel provided of peripheral projections, a line of perforations parallel to the binding line being provided allowing to remove any sheet without breaking the binding.

The invention has for further object an automatic machine performing the lying of the copying material, the printing of the sheets, the binding and the cutting off of the latter. Such a machine is characterized by the following features independently applied or applied in all combinations:

(a) Each spool of fresh paper passes through a printing device, is applied upon a delivering drum dipping in an inkstand and thence passes between a drying pressing scraper and a heating cylinder.

(b) The sheets provided with a carbon coating by the above means are then superimposed for passing under circular toothed knives which make perforations permitting to remove each sheet, thence pass between binding wheels and are finally cut off by circular knives, a suitable device separating, at a known manner, each multiple document.

(c) Regulating means are provided, for modifying the position or the pressure of the heating delivering cylinders, as well as the position and pressure of the scraper.

(d) The drying pressing scraper is constituted by a blade introduced in a slot provided in a corresponding support, setting screws permitting of keeping a perfectly plane, the pressing scraping heating plate.

The invention relates also to other features which will appear in the following description in reference to the accompanying drawings given by way of example only.

Fig. 1 is a perspective view of a machine according to the invention.

Fig. 2 is a perspective view, at an enlarged scale, of a drying pressing inking device.

Fig. 3 is a perspective view, at an enlarged scale, of a device for perforating, binding and cutting off the sheet coated with carbon.

Fig. 4 is a lateral view, with sectional view 100 showing with more details, the unit illustrated in Fig. 2.

Fig. 5 is a front view of the heating drying scraper.

Fig. 6 is a transverse sectional view of the heating drying scraper mounted in its support.

Fig. 7 is a front view of a blade limiting the thickness of the material on the delivering drum.

Fig. 8 is a front view of the delivering drum.

Fig. 9 is a partial perspective view of a file of 110

printed forms coated with carbon and manufactured with the automatic machine.

As previously stated, the process for manufacturing carbon papers consists chiefly in the incorporation of the copying material in the paper, by pressure in a hot state and realized by means of a drying pressing scraper which removes at the same time the material in excess. The drying of this material simultaneously with its incorporation allows to obtain:

(a) A paper coated with carbon which does not maculate and which does not necessitate an important pressure, such as that produced by a pencil-joint or by a character of typewriter when making a report.

(b) Successive impressions more numerous than those obtained with ordinary carbon papers.

(c) Not blurred printing as is ordinarily the case for the last typed sheets.

(d) Carbon papers which, from their nature, may be stacked without giving rise to the inconveniences of the ordinary carbon papers which must be stacked on edge or put into boxes.

The machine hereafter described by way of example only, allows the realization of files of printed forms coated with carbon from spool of fresh paper. These files of printed forms are wholly and automatically manufactured by the machine which delivers at its delivering end files of printed forms coated with carbon, put together and counted.

This machine comprises a main frame 1 upon which are mounted the different devices. In the example shown, the files of printed forms are constituted by three sheets printed on one of their faces, two of this sheets having on the other face a laying of copying material.

The three sheets superimposed and assembled 2, 3 and 4, are fed out automatically from spools 2a, 3a and 4a mounted on corresponding supports. Any number of spools can be provided, this member is a function of the member of each document coated with carbon; also, the colour of this paper can vary according to the spools and the destination of these documents.

The machine comprises for laying the copying material to units 5 one of which is more particularly shown in perspective view at Fig. 2 and in transverse sectional view at Fig. 4. The machine includes also several printing devices of printed forms printing characters and other. These devices which are shown at 6 in Fig. 1 do not necessitate a special description as they are of a usual type which does not contemplate the invention.

It would thereafter be described a unit 5 for incorporating the copying material into a sheet 4 for instance which has been previously printed by a known device 6.

In Fig. 4, the printed strip 4 which is guided by a roller 7 passes upon the rollers 8 and 9 for applying itself on a drum 10.

The copying material is laid upon the sheet 4 by a drum 11 which dips in a container or inkstand 12, a plate 13 limiting the amount of ink on the drum 11.

In the example shown, files of double printed forms are simultaneously realized which are subsequently separated. The inking drum 11 is shaped as shown in Fig. 8 for lying down two layers separated by a space 14. The plate 13 limiting the amount of ink is adjustable on its support 15 (Fig. 7) and provided with tongues 16 which pass between the useful parts of drum 11 at the ends of the same. The spindle of the drum 11 is mounted on a rocking member 17

(Fig. 2) which allows, by the intermediary of the threaded rod 18 and the nuts 19 and 20, to adjust the position of the inking drum 11 for lying more or less material upon the strip 4.

The copying material laid upon the strip 4 by the inking drum 11 is incorporated into the paper by means of a drying pressing scraper 21 which removes at the same time the excess of material which falls down into the inkstand 12.

This drying pressing scraper 21 is mounted in a slot 22 of a support 23 pivoted at its ends by the intermediary of eccentric weights 24. The drying pressing scraping blade is maintained in its support 23 by means of screws 25 which allow by adjusting them to maintain the blade 21 perfectly plane. This latter device constitutes one of the features of the invention.

Then the strip 4 treated as just stated passes on the roller 26 on which it is gripped by the roller 27 but only in the parts not coated with materials.

It is to be noted, according to the invention, that the drums or rollers 10-11 are heated as well as the inkstand from a suitable source and preferably by means of electrical resistances, the connection wires of which are indicated at 28.

The pressure of the drying pressing scraper is adjusted by means of the screw 29 which varies the stretching action of the spring 30 fixed to the support 23.

The inkstand 12 is fed from a tank 31 heated by means of a pipe 32 heated itself and controlled by a valve.

The strips provided with the copying material and dried as previously stated are superimposed at 33 (Fig. 3) and pass simultaneously under toothed circular knifes 34 and 25 which realize perforations permitting to detach any sheet without breaking the binding of the files of printed forms. The superimposed strips pass subsequently between wheels 36 provided with peripheral projections which perform a binding and finally pass under side circular knifes 37 and 38 and a central circular knife 39. The strips so bound together are finally cut off by a blade 40 at a known manner.

Fig. 9 illustrates more particularly a file of printed forms coated with carbon and manufactured with the machines previously described. This file is constituted by three sheets 2b, 3b and 4b bound together at 41 by pressing between wheels 36 and provided with perforations 42 preferably adjacent to the binding line for the purpose already indicated.

It is obvious that the embodiment of the machine for carrying out the process and the manufacturing of file of printed forms coated with carbon is a mere example able of numerous modifications which so long as they do not change the features previously stated nor the purpose aimed, are comprised in the scope of the invention.

What I claim as my invention and desire to secure by Letters Patent is:

The process of coating paper with copying material consisting in applying heated copying material in a liquid form to one surface of a strip of paper, passing the paper so treated around a heated roller with the untreated surface of the paper contacting with the roller to dry the paper, and applying a scraper under pressure to the treated surface of the paper on the heated roller to press the paper against the roller to force the liquid copying material into the body of the paper while the latter is being dried on the roller, and said scraper also operating to remove the excess of liquid copying material from the paper.

ARMAND DEPLANCHE. 150
